UNITED STATES PATENT OFFICE

HERBERT S. JANDUS, OF DETROIT, MICHIGAN, ASSIGNOR, BY MESNE ASSIGNMENTS,
TO GENERAL SPRING BUMPER CORPORATION, A CORPORATION OF MICHIGAN

DESIGN FOR AN AUTOMOBILE BUMPER

Application filed March 17, 1924. Serial No. 8,968. Term of patent 14 years.

To all whom it may concern:

Be it known that I, HERBERT S. JANDUS, a citizen of the United States, residing at Detroit, in the county of Wayne and State of Michigan, have invented a new, original, and ornamental Design for Automobile Bumpers, of which the following is a specification, reference being had to the accompanying drawing, forming part hereof, wherein

Fig. 1 represents a plan view and Fig. 2 a front elevation of a bumper exhibiting my new design.

I claim:

The ornamental design for an automobile bumper, as shown.

HERBERT S. JANDUS,
